UNITED STATES PATENT OFFICE.

EDWARD J. DOBERSTEIN, OF BLUE ISLAND, ILLINOIS, ASSIGNEE TO GOODMAN MANUFACTURING COMPANY, OF CHICAGO, ILLINOIS, A CORPORATION OF ILLINOIS.

FLITTING DEVICE.

Application filed December 25, 1926. Serial No. 157,001.

This invention relates to improvements in transportation devices for mining machines, and has for its principal object to provide a simple and efficient auxiliary draft means for transporting kerf cutting mining machines from one place to another over mine bottoms for greater distances and at a higher rate of speed than is ordinarily possible with mining machines of this character.

My invention is more particularly adapted for use in connection with mining machines of the continuous kerf cutting or shortwall type used especially for undercutting coal in mine rooms using the room and pillar system of mining and comprises a detachable auxiliary draft or power device for transporting the mining machine over the mine bottom from cutting place to cutting place. The auxiliary draft device is provided with a detachable power connection from the mining machine. The operation of transporting a mining machine as described intermediate the cutting places is generally known as "flitting". The mining machine and the auxiliary draft device may be carried bodily upon a wheeled mining machine truck, which is provided with detachable power connections to the auxiliary draft device, whereby the entire apparatus may be readily transported from room to room along mine tracks in the usual manner. Further objects and advantages of my invention will appear from time to time in the course of the following description.

The invention may be more readily understood by reference to the accompanying drawings illustrating one form in which my invention may be embodied, wherein:

Figure 1 is a top plan view of the cutting apparatus including a cutting mechanism of the shortwall type, connected to the auxiliary draft device, as embodied in my invention, both being carried upon a mining machine truck;

Figure 2 is a side elevation of the apparatus as shown in Figure 1;

Figure 3 is a side elevation of the auxiliary power device having parts broken away and part in section, to show the drive connections from the motor of the cutting mechanism;

Figure 4 is a transverse section through the auxiliary power device taken on line 4-4 of Figure 1; and

Figure 5 is a diagrammatic view illus-

trating a typical method in which my apparatus may be utilized in a room and pillar system of mining, showing the various positions of the parts of the apparatus while sumping and making the transverse cut.

Referring now in detail to the drawings, a cutting mechanism of the shortwall type is indicated at 10, being carried and supported upon a wheeled truck 11 of the usual type and construction. The cutting mechanism 10 is provided with an underframe 12, upon which said cutting mechanism is mounted for sliding movement over the mine bottom. Said cutting mechanism is provided with the usual cutting element, comprising a longitudinally extending cutter bar 13, having an endless cutter chain 14 (not shown) mounted thereon. The cutting mechanism is sumped and fed across the working face by means of flexible draft ropes 15 and 16, actuated by their respective rope drums 17 and 18. Either of the drums for the flexible feeding mechanism may be selectively driven from a motor 19, as desired. Both the cutting and flexible feeding mechanism are driven through suitable gearing from said motor. The operating mechanism for the cutting element and the flexible draft feeding means need not be herein described as it forms no part of the present invention, excepting to point out that an auxiliary draft device 20 has detachable power connections with said motor.

The auxiliary draft device is composed of a sliding shoe or skid 25 having longitudinally extending channels 26, 26, disposed at the lateral edges thereof, said flanges being directed toward each other. The forward end of the upper flanges of said channels are cut away so as to permit the tongue extensions or channels 27, 27 to be secured to the web portion of said first mentioned channel. Said auxiliary draft device is detachably connectible with the under frame 12 of the cutting mechanism as will now be described.

The underframe of the cutting mechanism is composed of a pair of transversely spaced channel members 28, 28, extending along the lateral edges of said cutting mechanism. The channels have the flanges turned inwardly toward each other and are connected together by a shoe or base plate 29 secured to the lower flanges. Guide plates 30, 30, are attached to the inner sur-

faces of said flanges adjacent the rear end thereof, affording sliding and guiding engagement therein of said tongue extensions 27, 27, of the auxiliary draft device. This arrangement is such as will positively align the respective shoes or base plates of the cutting mechanism and auxiliary draft device, thereby providing a continuous shoe or sliding surface for conjointly sliding the cutting mechanism and auxiliary draft device universally over mine bottoms.

Coupling devices for the auxiliary draft device and cutting mechanism are provided at each side and include bracket members 35, 35, pivotally mounted on the outside of the web portion at the forward ends of the channels 26, 26, of the auxiliary draft device. Said brackets are adapted to be detachably connected to brackets 36, 36, which are secured on the outside of the channels 28, 28, by means of screw members 37, 37. This coupling connection remains in engagement when the cutting mechanism is to be flitted from place to place, but is disengaged during sumping or other cutting operations.

The draft mechanism of the auxiliary draft device may be driven from the motor of the cutting mechanism in any suitable manner. As herein illustrated in Figure 3, said draft mechanism includes a gear reduction unit, such as worn gearing, for driving a vertically disposed shaft 40 which has a bearing support in an arm or bracket extending from the worm gear housing, and the lower end of said shaft having bearing support in the shoe or skid plate 25. A winding drum 41 is mounted on said shaft and is preferably of relatively large capacity so as to carry a cable 42 of a much greater length than that usually carried by the flexible feeding mechanisms of the mining machine. The gearing connections of said driving mechanism are such as will permit the winding drum to wind on or pay off the cable at a relatively high rate of speed, whereby the cutting mechanism, together with the auxiliary draft device may be moved over mine bottoms greater distances and at a higher rate of speed than is possible by the use of the flexible feeding mechanisms of the mining machine.

Guide devices for the cable 42 are provided on both the auxiliary draft device and the cutting mechanism for training said cable in either a forwardly or rearwardly direction. Said guide devices include a sheave 45 disposed in the forward end of the shoe or base plate 25 adjacent the channel 26 for receiving the cable 42 from the winding drum 41. Said cable is then trained forwardly over the swivel guide sheave 46 mounted on a pivot arm support which is attached to the forward corner of the cutting mechanism, thence over the head guide sheave 47 which is mounted on a U bracket

48 disposed around the cutter bar 13 and detachably secured thereto by a vertically disposed pin 49 extending through said cutter bar. The head guide sheave and U bracket are removed from the cutter bar before the sumping or cutting operation is commenced. A guide sheave 50 is centrally disposed at the rear end of the shoe or base plate 25 of the auxiliary draft device, over which the cable is trained directly from the winding drum 41 for drawing the complete mechanism in a rearwardly direction.

The mining machine truck 11 is adapted to transport the cutting mechanism and the auxiliary draft device bodily from place to place over mine tracks. Said truck is provided with a detachable driving connection through the auxiliary draft device to the motor of the cutting mechanism. This driving connection is similar to the usual drive of the truck from the cutting mechanism and details thereof need not be herein described.

The use and operation of my device is as follows:

The main entries of mines are usually provided with tracks 55, over which trucks carrying cutting mechanisms may be readily transported, but in many instances it is desirable to transport the cutting mechanism beyond the end of the tracks, as for example in mine rooms where it is not considered practical or economical to extend temporary tracks up to the working face as indicated at 56. Furthermore, the low coal seams or insufficient head room often prohibits the transporting of cutting mechanisms on trucks, in such mine rooms, in which case an auxiliary flitting device as herein described would permit the cutting mechanism to be drawn to and from the working face at a relatively high rate of speed.

The cutting mechanism and the auxiliary draft device are loaded or unloaded bodily from the truck as a unit. The cable 42 of the auxiliary draft device is trained over the guide sheaves and anchored adjacent the face. Power is then applied to said cable whereby the machine is drawn forwardly. Adjacent the face the cutting device is disconnected from the auxiliary draft device, and makes a cut in the face in the usual manner. The complete mechanism is flitted rearwardly in the same manner as forwardly except that the cable is trained in a rearwardly direction.

A horizontally disposed winding drum of large diameter as embodied herein, permits a relatively high rate of flitting speed or cable speed as well as a greater cable capacity. Further, the arrangement is such as will eliminate the necessity for a spooler guide for directing cable on and off the drum. The driving mechanism with the horizontal winding drum afford a compact arrangement

whereby the complete auxiliary draft device may be disposed in closer relation relative to the cutting mechanism, thereby reducing the overall length of the complete unit, and making it easier to maneuver the complete unit about the mine.

Although I have shown and described one form in which my invention may be embodied, it will be understood that the construction thereof and arrangement of the various parts may be altered without departing from the spirit and scope thereof. Furthermore, I do not wish to be construed as limiting myself to the specific embodiment illustrated in the drawings, excepting as it may be limited by the appended claims.

I claim as my invention:

1. In combination with a cutting mechanism having a flexible draft feeding means and a motor for operating the same, an underframe for supporting said cutting mechanism for movement over mine bottoms, an auxiliary draft feeding device mounted on a shoe detachably connectible with the rear end of said cutting mechanism and adapted to be conjointly moved therewith over mine bottoms, said auxiliary draft feeding device including a winding drum disposed on a vertical axis and operatively connected with said motor for driving said feeding device at a greater rate of speed than said feeding means.

2. In combination with a cutting mechanism having a flexible draft feeding drum and a motor for operating the same, an auxiliary draft feeding device comprising a

winding drum disposed on a vertical axis and of greater capacity than said feeding drum, said auxiliary draft feeding device being detachably connectible to the rear end 40 of said cutting mechanism, and detachable gearing connections between said motor and said winding drums.

3. In combination with a cutting mechanism having flexible draft feeding means 45 and a motor for driving the same, an auxiliary draft feeding device comprising a vertically disposed shaft having a winding drum mounted thereon having a rope capacity greater than said feeding means, said 50 auxiliary draft feeding device being detachably connectible to the rear end of said cutting mechanism within the vertical limits thereof and forming therewith a continuous sliding shoe for movement over mine bottoms. 55

4. In combination with a cutting mechanism having a flexible draft feeding means and a motor for operating the same, an auxiliary flexible draft device comprising 60 speed reducing gearing operably connectible to said cutting mechanism, and a winding drum disposed on a vertical axis intermediate said gearing and said cutting mechanism, said draft device being detachably connectible to the rear end of said cutting mechanism. 65

Signed at Chicago, in the county of Cook and State of Illinois, this 23rd day of December, A. D. 1926.

EDWARD J. DOBERSTEIN.
